Specification for Design.

Patented Mar. 8, 1921.

Application filed July 31, 1920. Serial No. 400,547. Term of patent 3½ years.

To all whom it may concern:

Be it known that I, ROMAN MELLNIK, a citizen of Russia, and a resident of Young, in the Province of Saskatchewan and Dominion of Canada, have invented a new, original, and ornamental Design for a Watch-Chain, of which the following is a specification, reference being had to the accompanying drawings, forming part thereof.

Figure 1 is a front elevation of a watch chain, showing my new design, and Fig. 2 is a rear view thereof.

I claim,—

The ornamental design for a watch chain, as shown.

ROMAN MELLNIK.
